UNITED STATES PATENT OFFICE.

RICHARD WEBB BURNETT, OF MONTREAL, QUEBEC, CANADA.

DUMP-CAR DOOR.

1,089,392.

Specification of Letters Patent. Patented Mar. 10, 1914.

Application filed April 13, 1912. Serial No. 690,571.

To all whom it may concern:

Be it known that I, RICHARD WEBB BURNETT, a citizen of the United States of America, residing at the city of Montreal, 5 in the Province of Quebec, Dominion of Canada, have invented certain new and useful Improvements in Dump-Car Doors; and I do hereby declare that the following is a full, clear, and exact description thereof.

10 My invention relates particularly to the means whereby the dump doors of dump cars are sealed and it has for its object to increase the sealing qualities of the joints between the side edges of the doors and the

15 door frames without the necessity of altering the construction of the usual flanged door opening.

The invention may be said briefly to consist of pockets formed at the side edges of a 20 dump door and adapted to receive the side flanges of the door opening and form an effective seal between such parts. For full comprehension, however, of my invention reference must be had to the accompanying 25 drawings forming a part of this specification in which similar reference characters indicate the same parts, and wherein:

Figure 1 is an enlarged detail sectional perspective view of the meeting edges of the door and door frame taken on line A A 30 Fig. 2; and Fig. 2 is a transverse vertical sectional view of a portion of the floor structure of hopper formation of a grain car having a door provided with my invention.

I have illustrated my invention applied 35 to a type of a hopper *b* and door *c* in which the door is when closed in a nearly vertical plane but I do not claim this structure as it forms the subject-matter of a separate application filed by me on October 17, 1911, 40 under Serial No. 655,253.

According to my present invention the door is of trough form the side flanges being indicated at *d* and pockets are formed at the side edges by angular plates *e*, the horizontal legs of which are riveted as at *f* to the bottom of the door while the angular plate extends from end to end of the latter. As the member *e* is attached outside of the flange *d* it affords no obstruction to the discharge of the lading.

What I claim is as follows:—

In a car for loose commodities a discharge hopper having walls with straight side edges, and a door hinged at one edge to the 55 hopper and having side flanges with pockets having flared mouths and said pockets being adapted to envelop and closely fit the side edges of the walls when the door is closed.

In testimony whereof I have signed my name to this specification in the presence of two witnesses.

RICHARD WEBB BURNETT.
